J. PENROD ET AL

PUMPING EQUIPMENT

Filed March 20, 1925

UNITED STATES PATENT OFFICE.

JOHN PENROD AND ROBERT D. THOMPSON, OF OKMULGEE, OKLAHOMA.

PUMPING EQUIPMENT.

Application filed March 20, 1925. Serial No. 17,019.

This invention relates to pumps especially adapted for use in wells, and is a continuation in part of our application, Serial Number 709,746, filed April 29, 1924.

5 The pumps we manufacture are provided with a cast iron barrel in which the plunger reciprocates, and this barrel is sometimes broken or crushed when a wrench is applied thereto for either attaching or detaching the 10 barrel thereby rendering the barrel unfit for further use.

Therefore, an important object of this invention is to provide a barrel having a separate attaching coupling of suitable stout 15 and hard metal by means of which the same may be connected to the bushing or detached therefrom without the possibility of crushing or cracking the barrel.

A further object of the invention is to 20 provide an attaching coupling for a working barrel which not only provides a strong wrench contact surface, but also provides an enlarged chamber for the reception of a standing valve whereby the free movement 25 of the fluid upwardly through the barrel from the standing valve is provided for.

Also an important aim of the invention is to provide a bushing having its ends provided with stepped threaded surfaces so 30 located and arranged that the machine work necessary to finish the bushing is reduced to a minimum.

A further object of the invention is to provide a pump which is of highly simplified 35 construction, easy to handle and durable in use.

Other objects and advantages will be apparent during the course of the following description.

40 In the accompanying drawing forming a part of this application, and in which like numerals are employed to designate like parts throughout the same—

Fig. 1 is a fragmentary sectional view 45 through a pump, the view illustrating the improved bushing and coupling and the enlarged chamber for the reception of the standing valve.

Fig. 2 is a group perspective illustrating 50 the improved coupling and bushing.

In the drawing wherein for the purpose of illustration is shown a preferred embodiment 55 of the invention, the numeral 5 designates the improved pump consisting of a shell 6, upper and lower bushings 7 and 8 respec-

tively, a standing valve 9, and a plunger 10.

Referring first to the lower bushing 8 it will be seen that the same is provided with stepped surfaces 11, 12 and 13 at the upper portion thereof, which stepped surfaces are 60 separately threaded while the bushing is attached to the chuck of a lathe. That is to say, the casting from which the bushing 8 is formed is attached to the chuck of a lathe, and while in this position the threads on the 65 stepped surfaces 11, 12 and 13 are separately cut. Thus with one application of the bushing to a chuck, the surfaces 11, 12 and 13 may be provided with threads thereby avoiding the necessity of setting up the 70 job anew for each thread to be cut.

When the threads on the surfaces 11, 12 and 13 are properly formed the bushing is reversed and again applied to the chuck and the threads 16 and 17 formed in the bore 75 18 of the bushing, all without removing the bushing from the lathe. Therefore, all the internal and external threads on the bushing 8 may be applied with only two chuck operations. The internal threads 16 and 17 are 80 employed for connecting the members 20 and 21 of a gas anchor to the bushing. By attaching the members 20 and 21 to the inside of the bushing 8 the lower portion 25 of the bushing is left entirely free for the application of a wrench thereto.

The barrel 30 is provided at its lower end with an attaching coupling 31 of a suitable stout steel or other metal of a greater internal diameter than the internal diameter 90 of the barrel 30 whereby to provide an enlarged chamber for the reception of the standing valve 9. The standing valve 9 is positioned within the coupling 31 as shown in Fig. 1, so that the fluid may easily pass 95 through the standing valve and up into the working barrel. In other words, the enlarged coupling 31 provides a generous space about the standing valve 9 so that the movement of the fluid upwardly into the barrel 100 is not in any way obstructed.

After the barrels have been in use for some time it may be necessary to renew the standing valve 9 or other part of the barrel, and to do this, it is merely necessary to remove the shell 6 and apply a wrench directly to the steel coupling 31 and turn the same with sufficient force to remove the coupling from engagement with the stepped surfaces 12. The operator can do this with- 110

out the possibility of danger to the barrel as the coupling 31 is possessed of sufficient strength to withstand the strain. As previously stated, the application of a wrench directly to the cast iron barrel 30 would be likely to crack or crush the same and render the barrel unfit for further use.

It is thus seen that the attaching coupling 31 not only provides a more durable connection for the barrel 30, but also an enlarged chamber for the reception of the standing valve and a means whereby the life of the pump is greatly lengthened.

Claims:

- 15 1. In a pump having a working barrel, a shell and a standing valve cage, a body having a plurality of stepped surfaces, externally threaded for engagement by the shell, the working barrel and the standing 20 valve cage of a pump.
- 20 2. A well pump comprising a shell, a working barrel, a standing valve cage, inner

and outer anchor members, and a bushing having one end portion provided with a plurality of stepped surfaces, all of which 25 are externally threaded to adapt the same for engagement by the shell, working barrel and standing valve cage, the other end portion of the bushing being internally threaded to adapt the same for engagement by the 30 inner and outer anchor members.

3. In a well pump, a bushing provided with a plurality of stepped surfaces, a shell detachably engaged with one of said surfaces, a cast iron working barrel entering 35 the shell and terminating short of the bushing, and a short coupling sleeve made from steel and connected to the barrel and detachably engaged with the other of said surfaces.

In testimony whereof we affix our signatures.

JOHN PENROD.
ROBERT D. THOMPSON.
